United States Patent Office.

WILLIAM WICKERSHAM, OF BOSTON, MASSACHUSETTS.

Letters Patent No. 63,774, dated April 9, 1867.

IMPROVED EGG-BEATER.

The Schedule referred to in these Letters Patent and making part of the same.

Be it known that I, WILLIAM WICKERSHAM, of Boston, in the county of Suffolk, and State of Massachusetts, have invented a new and useful improvement on the Egg-Beater; and I hereby declare that the following is a full, clear, and exact description of the construction and operation of the same, reference being had to the annexed drawings, making a part of this specification, in which—

Figure 1 shows a side elevation exhibiting the segment gear crank connection-rod, &c.

Figure 2 shows a side sectional view of the same; and

Figure 3 shows a cross-section of the flattened knives or beaters.

a is a frame, to which the different parts of the machine are attached; *b* is a segment gear; *c c, &c.*, are the beating-knives; *d* is the crank; *e* is a connection-rod, connecting the crank with the segment gear in such manner as to give to said gear an oscillating motion when the crank is turned; *f* is the handle; *g* is a small shaft, to which the pinion *h* and the beaters *c c* are attached.

My egg-beater operates as follows: The operator takes hold of the crank-handle *f* and turns the crank round continuously, and by means of the connection-rod *e* attached to the outer end of the crank at *f* and to the segment gear at the point *e*, a vibratory motion is given to the segment gear *b*; and as the teeth of this segment gear work in the teeth of the pinion *h*, which is fastened on to the same shaft with the beaters *c c, &c.*, said beaters are made to turn round one way when the segment gear vibrates one way, and the beaters will move the other way when said segment vibrates in the other direction, and continuously the reverse vibration of the segment reverses the motion of the beaters.

My invention consists in the device for imparting a vibratory motion to the segment gear *b*, that is, the crank *d* and the connection-rod *e*, connected and arranged as described.

I do not claim the alternate forward and backward movement of the beating-knives, as I am aware that such motion has been given them before, but what I do claim as my invention, and desire to secure by Letters Patent, is—

The device in egg-beaters of giving the segment gear (and, consequently, the beater-knives *c c c*,) a vibratory motion by means of a crank and connection-rod formed and arranged as described.

W. WICKERSHAM.
